UNITED STATES PATENT OFFICE.

CARL BAUKNECHT, OF PARIS, FRANCE, ASSIGNOR TO THE HAMBURG
AMERIKANISCHE UHRENFABRIK, OF SCHRAMBERG, GERMANY.

BELL.

SPECIFICATION forming part of Letters Patent No. 718,241, dated January 18, 1903.

Application filed October 6, 1902. Serial No. 126,132. (No model.)

To all whom it may concern:

Be it known that I, CARL BAUKNECHT, a subject of the King of Würtemberg, Germany, residing at Paris, France, have invented certain new and useful Improvements in Alarm-Clocks, of which the following is a specification.

The present invention has reference to alarm-clocks, and relates more especially to alarm-clocks with swinging bells or gongs; and the object of the invention is to suspend the bell in such manner that the weight of the bell parts above and below the axis of suspension is approximately equal, thereby minimizing the power necessary to actuate the alarm.

With this object in view the invention consists of the construction and arrangement of parts to be hereinafter described, and particularly set forth in the appended claims, reference being had to the accompanying sheet of drawings, of which—

Figure 1 shows a vertical sectional elevation through the alarm device according to the present invention in the position of rest. Fig. 2 is a horizontal sectional view on line A B of Fig. 1. Fig. 3 is a vertical sectional elevation turned at an angle of ninety degrees to Fig. 1. Fig. 4 shows a vertical sectional elevation of the device in operation.

The support *s* is secured with its base to the clockwork-housing *f*. The support at its upper end is forked and journals the pivotal axle *d*, upon which is secured the screw-bolt support *n*, carrying the bell or gong *k*. The handle *x* serves to clamp the bell to the bolt-support and is so constructed that it counterbalances the weight of the bell parts above and below the pivotal axle *d*, giving the lower part just enough overweight to cause the bell to ordinarily hang in a vertical position.

For the purpose of starting and keeping up oscillating movements of the bell the pivotal axle *d* carries a rigid finger *i*, with a rectangularly-extending fork *r* loosely embracing the upper end of the clapper-rod *m*. The clapper *h* is secured in the clamping-head *b*, pivotally secured upon the stud *t* on the support *s*.

All of the described mechanism is secured

upon the support *s*, and the only connection with the clockwork and the alarm mechanism is the fork *g*, fast upon the clockwork-arbor *a*, which with its upper rectangularly-bent part loosely embraces the finger *i* and upon being oscillated causes the bell mechanism to oscillate about the pivots *d* and *b*, as shown in Fig. 4.

The bell *k* and the clapper *h* always swing toward each other the actuating-clock-work power need only be comparatively little.

Appropriate means are to be provided for returning the bell into the vertical position when at rest.

What I claim, and desire to secure by Letters Patent, is—

1. In alarm-clocks, the combination of a support secured to the clockwork-housing, a pivotal axle journaled in said support, a screw-bolt support fast upon the said pivotal axle, a bell, a handle, forming a counterbalance and clamping the said bell to the said screw-bolt support, and means for oscillating the said pivotal axle, substantially as and for the purpose set forth. 75

2. In alarm-clocks, the combination of a support secured to the clockwork-housing, a pivotal axle journaled in said support, a screw-bolt support fast upon the said pivotal axle, a bell, a handle, forming a counterbalance and clamping the said bell to the said screw-bolt support, a stud secured to the said support, a clamping-head pivotally secured to the said stud, a clapper, secured in the said clamping-head, a finger secured to and depending from the said pivotal axle, a fork rectangularly extending from the said finger and loosely embracing the upper free end of the clapper-rod, and means for actuating the said depending finger, the parts being constructed, arranged and working substantially as and for the purpose set forth. 85 90

In testimony that I claim the foregoing as my invention I have signed my name in presence of two subscribing witnesses.

CARL BAUKNECHT.
